VEGETABLE BIN

John W. Ebstein, Roslyn Heights, N.Y., assignor, by mesne assignments, to Federal Enameling & Stamping
Co., Pittsburgh, Pa., a corporation of Michigan

Filed Feb. 10, 1960, Ser. No. 59,342

Term of patent 14 years

(Cl. D44—1)

FIG. 1.

FIG. 2.

FIG. 3.

FIG. 4.

FIG. 5.

Figure 1 is a perspective view of a vegetable bin showing my new design;

of Figure 2.

I claim:

The ornamental design for a vegetable bin, as shown.
